D. C. Stickney
Attorney

UNITED STATES PATENT OFFICE.

ALFRED J. WOOD, OF WALDWICK, NEW JERSEY, ASSIGNOR TO UNDERWOOD TYPE-WRITER COMPANY, OF NEW YORK, N. Y., A CORPORATION OF DELAWARE.

TYPEWRITING MACHINE.

1,418,506.

Specification of Letters Patent. Patented June 6, 1922.

Application filed December 17, 1920. Serial No. 431,324.

To all whom it may concern:

Be it known that I, ALFRED J. WOOD, a citizen of the United States, residing in Waldwick, in the county of Bergen and State of New Jersey, have invented certain new and useful Improvements in Typewriting Machines, of which the following is a specification.

This invention relates to means for feeding a bill-sheet or work-sheet relatively to a record-sheet, which may be a tally-strip. It is frequently the case in machines comprising such means that the work-sheet is fed around the platen at a different rate than the tally-strip, for it is desirable that the items on the work-sheet be double or triple spaced, whereas the items on the record-sheet or the tally-strip should generally be condensed by single-spacing.

The ordinary pressure rolls press so strongly against the platen that if a work-sheet is rapidly withdrawn from the machine, the tally-strip is apt to be dragged with it, even in cases where the pressure rolls do not act directly on the tally-strip, as in the patent to Hart, 1,281,160, dated October 8, 1918. This invention contemplates the removal of the usual pressure rolls and the utilization of small rolls adapted to press against annular inserts of soft rubber, imbedded in the hard rubber platen surface and flush therewith. By the use of rolls pressing against such inserts, a more effective grip or bite is provided than is obtained by the pressure of rolls against the usual hard rubber surface. Much less pressure would have to be applied to the rolls against the soft inserts to obtain an effective grip, and thus the dragging action on the tally-strip described above may be reduced.

The rolls which co-operate with the soft inserts are preferably mounted at the front of the platen. It is an object of this invention to utilize substantially the full printing range of the platen for the tally-strip, and since the bill-sheet is fed independently of said strip, the rolls must be positioned outside the limits of the strip, or beyond the printing field, and near the ends of the platen.

The Hart patent illustrates an underlying tally-strip which is much narrower than the printing field of the platen. The feed-rolls shown in the Hart patent press broad mar-

gins of an overlying work-sheet against the hard printing surface of the platen. When using a tally-strip which covers the printing field of the platen for its entire width, however, a difficulty arises because of the necessarily slight difference between the width of the tally-sheet and the width of the overlying bill or other work-sheet. This slight difference in width affords only very narrow margins on the bill-sheet that are serviceable to be pressed against the platen, for controlling the feed of the bill-sheet. The difficulty therefore arises of holding the bill-sheet against the platen under such circumstances. This difficulty is overcome by feeding the work-sheet solely by the use of small pressure-rolls at the ends of the platen to press the overlying bill-sheet against the inlaid soft rubber rings. This device successfully controls a wide work-sheet by means of only the narrow side margins thereof. Said rubber rings do not bulge from the surface of the platen, so that the work-sheet may lie snugly against the platen. In said Hart patent, the feed-rolls are far below the printing point, and, in attempting to use them for seizing the narrow margins of wide bill-sheets, said sheets are found to bulge out from the platen above said rolls to a serious extent; but the desired result can be obtained and the bill-sheets controlled successfully by the narrow margins thereof, and bulging at the printing point can be prevented by the use of the described small side rolls at points just above the printing line on the platen.

The present invention is shown as applied to an Underwood tally-strip machine as described in said patent to Hart; but it is understood that the device can be applied to other machines where relative shifting of sheets of varying widths is desired.

Other features and advantages will hereinafter appear.

In the accompanying drawings, Figure 1 is a front elevation of the invention applied to the machine, only the necessary co-operating parts of the machine being shown.

Figure 2 is a vertical section of Figure 1, showing, in addition, the tally-strip winding and feeding devices.

Figure 3 is a detail view of the platen showing the modified surface.

A platen 1, having a hard rubber surface

2, is mounted upon a shaft 3 journaled in the end-walls 4 of a frame forming a part of the usual typewriter carriage. The platen may be rotated by finger-wheels 5 or by the 5 usual ratchet wheel 6, which is engaged by slide 7 provided with a pawl 8, said slide being operated by a line-space lever (not shown) of the usual type.

Upon the end-walls 4 of the carriage are 10 mounted frames 11, which support the tally-strip feeding and winding mechanism. The details of this mechanism are described in the Hart patent, No. 1,281,160, referred to above, and comprise a pawl 12 adapted to 15 be operated simultaneously with the line-space slide operating a ratchet wheel 13 mounted on a shaft which has a gear wheel 14 fixed at its other end. The gear wheel 14 meshes with gear wheel 15 fixed to the winding 20 pulley which rolls up the used tally-strip as it is unwound from feed pulley 16.

Figure 1 shows the relative positioning of work-sheets 21 with respect to tally-strip 22. It will be noted that the usual pressure rolls 25 of the ordinary machine have been completely removed. It will be further observed that the tally-strip utilizes practically the full printing range of the platen, and, since no pressure rolls contact there- 30 with, its movement is independent of the rotation of the platen. Outside the limits of the space occupied by the tally-strip, the platen is provided with two grooved portions 23 into which are inserted bands or 35 inlays 24 flush with the surface of the platen. These bands are of soft rubber, or of other material considerably softer and more clinging than the hard rubber surface of the ordinary platen, producing an exceptionally 40 strong gripping action when pressure rolls are applied thereto. Much less pressure would have to be applied to these soft inserts than to the hard rubber surface in order to make an effective bite for the feeding 45 of sheets, and thus the bill-sheet can be withdrawn from the machine against this comparatively light pressure without dragging the tally-strip with it.

Adapted to co-operate with these soft rubber bands are rolls 25. These rolls may be supported against the platen in any position either below (see 25^a), as in the case of ordinary pressure rolls, or at the front. The latter position, is to be preferred, for, as 55 pointed out above, the bill-sheet is practically the width of the platen and is held at its ends. The sheet tends to bulge immediately after passing the rolls, and if the rolls were positioned as indicated at 25^a, the 60 sheet would bulge when it reached the printing point. The rolls are therefore mounted at the front of the platen to obviate this objection. The rolls 25 may be supported against the platen in any suitable manner, 65 but are here shown as mounted in brackets

26 on downwardly-extending fingers 27, which act as paper guides, said fingers being fixed to rearwardly-extending arms 28 terminating in members 29 journaled on and movable along a rod 30 fixed in the end-walls of the carriage frame. Each member 29 terminates in a U-shaped portion, having a small rod 31 slidable vertically therein and pressed upward by a spring 32 into a groove 33 in the lower portion of rod 30. When 75 arms 28 are in the position shown in Figure 2, the rods 31 engage the groove 33 to hold the rolls in lower or effective position. Upon rotation of the arms 28, the rods 31 disengage the groove and the rolls may be 80 swung upwardly to ineffective position. Each arm is shown as extending forwardly a distance such that sheets 21 and 22 will not be directed too far rearwardly before passing to the winding mechanism. From the 85 above description, it is obvious that rolls 25 may be adjusted along the platen, by sliding members 29 along rod 30 until the rolls are in contact with the soft rubber bands, each roll for its entire length engaging the rubber band or rim, and not running upon the hard platen at any point. The springs 32 may be made of sufficient tension to secure the necessary bite between the rolls and the rubber bands. The ordinary pressure rolls, 90 in order to produce the effective gripping action, press so heavily against the hard rubber surface of the platen that the withdrawal of the bill-sheet drags the tally-strip with it. These pressure rolls have therefore 100 been removed. In the present invention, the pressure of the rolls 25 against the soft rubber bands necessary to produce an effective gripping action need not be so strong, and the work-sheet may therefore be 105 withdrawn rapidly against such pressure without disturbing the position of the tally-strip.

Variations may be resorted to within the scope of the invention, and portions of the 110 improvements may be used without others.

Having thus described my invention, I claim:

1. The combination of a revoluble platen having a comparatively hard printing field 115 and provided outside of said field with soft rubber sheet-feeding bands or inlays flush with the platen, and means to co-operate with said soft rubber inlays to feed sheets around the platen only by means of narrow 120 side margins on said sheets, said co-operating means consisting only of rolls, one for each of the soft rubber inlays, each roll running only upon the soft rubber.

2. The combination of a revoluble platen 125 having a comparatively hard printing field and provided outside of said field with soft rubber sheet-feeding bands or inlays flush with the platen, and means to co-operate with said soft rubber inlays to feed sheets 130

- around the platen only by means of narrow side margins on said sheets, said co-operating means consisting only of rolls, one for each of the soft rubber inlays, each roll running only upon the soft rubber, said rolls arranged about at the printing line on the platen, to minimize or prevent bulging of sheets at the printing point. 35
3. In a typewriting machine comprising a carriage, in combination, a platen journaled in said carriage and having a comparatively hard surface around which work-sheets are adapted to be fed, said platen having circumferential grooves near the ends thereof, and a gripping device for feeding said sheets around said platen comprising two elements, one of said elements being of comparatively soft material in said grooves flush with the surface of the platen, and the other of said elements being pressure-rolls supported on said carriage and of a length to be pressed only against said bands, said rolls being the only elements pressing against said platen. 40
4. A condensed record typewriting machine comprising a revoluble platen and means to control the advance of sheets around said platen independently of each other, said sheets comprising a tally-sheet or strip overlaid by a wider work-sheet, said platen provided near its ends with circumferential soft rubber inlays, and separate feed-rolls to co-operate with said inlays to control said overlying work-sheet by means of its side margins outside of the tally-strip, 45 each feed-roll being of such length as to be confined to its soft rubber inlay; means being included for separately controlling the movement of the tally-strip around the platen. 50
5. A condensed record typewriting machine comprising a revoluble platen and means to control the advance of sheets around said platen independently of each other, said sheets comprising a tally-sheet or strip overlaid by a wider work-sheet, said platen provided near its ends with circumferential soft rubber inlays, and separate feed-rolls to co-operate with said inlays to control said overlying work-sheet by means of its side margins outside of the tally-strip, 55 each feed-roll being of such length as to be confined to its soft rubber inlay; means being included for separately controlling the movement of the tally-strip around the platen, said rolls being arranged at the front of the platen near the printing line, to prevent undue bulging of said work-sheet at the printing point. 55
